(57) **CLAIM**

We claim the ornamental design for a handheld vacuum attachment with ultraviolet light, as shown and described.

DESCRIPTION

FIG. 1 is a front profile view of a handheld vacuum attachment with ultraviolet light of our design.

FIG. 2 is a left side view of the embodiment of FIG. 1.

FIG. 3 is a right side view of the embodiment of FIG. 1.

FIG. 4 is a front view of the embodiment of FIG. 1.

FIG. 5 is a rear view of the embodiment of FIG. 1.

FIG. 6 is a top view of the embodiment of FIG. 1; and,

FIG. 7 is a bottom view of the embodiment of FIG. 1.

The broken lines in the Figures are for illustrative purposes only and form no part of the claimed design.
